UNITED STATES PATENT OFFICE.

THOMAS SPENCER MILLER, OF SOUTH ORANGE, NEW JERSEY.

ROPE-ENGINE FOR MARINE TRANSFERS.

1,037,508.

Specification of Letters Patent.

Patented Sept. 3, 1912.

Original application filed March 5, 1909, Serial No. 481,450. Divided and this application filed January 12, 1910. Serial No. 537,656.

To all whom it may concern:

Be it known that I, THOMAS SPENCER MILLER, a citizen of the United States, and a resident of South Orange, county of Essex, and State of New Jersey, have invented a new and useful Improvement in Rope-Engines for Marine Transfers, of which the following is a specification.

This application is a division of my prior application Serial No. 481,450, filed March 5, 1909.

I have fully and clearly illustrated my invention in the accompanying drawings to be taken as a part of this specification 15 wherein—

Figure 1 is a longitudinal section through a rope drum constituting an embodiment of my invention; Fig. 2 is a view in elevation partly in longitudinal section of another 20 embodiment of the same invention; Fig. 3 is a detailed view in elevation of the friction face of one of the drums.

Before proceeding with a detailed description of my invention I will state that 25 while the same is particularly adapted for use in connection with marine transfer apparatus of the general character or type forming the subject-matter of my application Serial No. 481,450, filed March 5, 1909, I desire it understood that the invention is 30 capable of general application wherever it would be advantageous to use a two-part drum having a slipping connection for one of its parts and I therefore do not desire 35 to be limited in any way to the use or combination set forth in my said application.

I will now proceed to describe the embodiments of the invention illustrated in the drawings, and referring to said drawings by characters of reference: 31 and 32 are the bearings in the frame for the shaft 33. The rope drum parts 16^a and 16^b are respectively loose upon the shaft and splined thereto so that part 16^a is freely 40 revoluble relative to the shaft, and the part 16^b is fixed thereto to revolve therewith in both directions.

34 is a cross key extending through a slot in the shaft bearing against a collar 45 35, which in turn bears against the end of the hub of the splined drum part 16^b.

36 is a set screw threaded into the end of

the shaft and thrusting against the cross key 34 through the pin 37.

55

38 is a lock nut.

39 is the spur wheel fast on the shaft, which meshes with a pinion on the engine crank-shaft.

By adjusting the set screw 36 the drum part 16^b is forced toward the drum part 16^a 60 and this in turn is forced toward the spur wheel 39. To provide the friction surfaces which, under the adjusted thrust of the set screw 36, transmit the power from the spur wheel to the drum part 16^a and also 65 from the shaft through splined drum part 16^b to the drum part 16^a, thus providing a drum part 16^a with double headed friction surfaces, I make the following provision: Between the drum parts 16^a and 16^b is the 70 friction ring 40 composed of an alloy of soft cast-iron and steel and also the friction ring 41 composed of cast steel. These rings are fast, respectively, to the drum parts 16^a and 16^b. Between the drum part 16^a and 75 the spur wheel 39 is the friction ring 42 of an alloy of soft cast-iron and steel and the friction ring 43 of cast steel, being fast, respectively, to the spur wheel and the drum part 16^a. Behind the friction ring 43 the 80 flange of the drum is provided with an annular air space 44 ventilated by a series of holes 45. The air entering the annular passage 44 through these holes comes directly in contact with the rear of the friction ring 43 opposite the friction surface and keeps it cool. A corresponding annular 85 passage 46 and ventilating holes 47 are provided in the body of the drum part 16^b at the back of the friction ring 41 for the cooling thereof. The friction rings 40 and 42 are both made in sections, as shown in detail in Fig. 3, the various sections being separated by radial spaces 48 connecting at both 90 ends with the open air so as to provide a 95 free circulation of air for cooling the sections. These friction rings are described and fully covered in my Patent No. 715,111, Dec. 2, 1902.

49 is an ordinary band brake operating 100 upon the flange of the drum part 16^a and, if need be, there may be another band brake operating upon the flange of the crank wheel 50.

The drum parts 16^a and 16^b and the friction rings 40 and 41 are preferably made of equal diameter, so that an undivided drum surface will be presented between the end flanges.

Although as above stated, the invention is capable of use in any situation where it is desired to have a positively actuated and a slip drum on the same shaft, the invention 10 is particularly applicable to the purpose such as described in my said application, and I will now set forth the operation thereof briefly, it being understood that, for example, the holding rope of a clam-shell 15 bucket is wound upon the drum part 16^a and the closing and hoisting rope on the part 16^b.

It will be understood that the set screw 36 is so adjusted that the pressure between 20 the friction surfaces is just sufficient to take up any slack in the rope which may be wound on the drum part 16^a, the two drum parts moving in unison except when an excessive pull occurs on the drum 16^a, or when 25 the band-brake 49 is applied to said part 16^a, at which time the part 16^a may slip relative to the driving gear and the drum part 16^b. If the operator desires to operate a clam-shell bucket to take a load, he would 30 permit the drums to pay out their ropes in unison until the bucket was in position to receive the load. He would then set the brake 49 which would arrest the drum part 16^a which would permit the blades of the 35 bucket to open in a manner which is well known without illustration. The brake is then released and the further motion of the engine lowers the bucket onto the pile. By then reversing the engine and thereby winding up the closing rope on the part 16^b, the 40 motion of the drum part 16^a being arrested by the pull on its rope caused by the load, the bucket is closed. When the bucket is closed the drum part 16^b will continue to 45 wind up the drum 3 and the bucket is hoisted to the height desired, the slack in the holding rope being taken up by the drum part 16^a. When the bucket is to be dumped the brake 49 is to be set to hold the drum part 16^a and the continued rotation of the part 16^b will cause the bucket to open, it being understood that the engine is reversed, so that the drum part 16^b pays out its rope.

The engine shown in Fig. 2 presents a 55 further very important invention, adding to the simplicity, economy and smallness of space required. In this construction there is a loose drum part 16^a, the splined drum part 16^b, the end flanges 51 and 52, the brake 49 and the shaft 33 with its bearings 31 and 32 as before. There are also the friction surfaces composed of the pair of friction rings 40, 41 and the pair of friction rings 42, 43. In this case, however the spur wheel

is dispensed with and in lieu thereof one of 65 the rings 42 or 43 is fixed to a spider 55, the hub 56 of which is splined to the shaft. Also in lieu of having one of the rings 40 or 41 fixed to the drum part 16^b, it is fixed 70 to a spider 57, the hub 58 of which is splined to the shaft. In this case the drum part 16^b may be keyed fast to the shaft.

To produce the endwise thrust I cut a thread 59 directly on the shaft and thread thereto a nut 60 and a like nut 61. By setting up these nuts the spider 55 binds the drum part 16^a toward the drum part 16^b so as to produce the requisite pressure between the friction surfaces. That this pressure may be yielding, I prefer to interpose 80 the coiled spring 62 between the spider 57 and the drum part 16^b. These springs also permit of the expansion of the parts under heat and maintains the friction pressure substantially constant under variations 85 from heat. However, these coiled springs 62 may, if desired, be dispensed with and also the spider 57, the friction ring 41 being, under those circumstances, made fast 90 to the drum part 16^b.

In the engine shown in Fig. 2 the cranks 63, 64 and crank disks 65, 66 and eccentrics 67, 68 are mounted directly on the drum shaft 33, and the additional brake 69 for occasional use is applied to the crank disk 66. 95

The cylinders 70 and 71 are made of very large bore sufficient to maintain the requisite pull in hoisting and swinging without the introduction of gearing, shafts and bearings. The brake 69 upon the crank disk or 100 fly wheel 66 controls the drum 16^b that is keyed to the shaft while the loose drum 16^a is controlled by the brake 49 acting directly upon it. The steam reverse valve 72 is of well known construction and is operated by 105 hand lever 73. Lever 73 together with foot-lever 74 for operating brake 49 and foot lever 75 for operating brake 69 are arranged in the most convenient position for the operator.

While in the preferred form of the invention I have shown and described the friction surfaces between the drum parts as being of the same diameter as the drum parts, I do not desire to be limited as to the exact 115 diameter of these frictions or the area of the engaging faces thereof, as they may be of less diameter than the drum parts, for instance as shown in Fig. 2 of the drawings, nor do I limit myself to separate elements 120 having the friction surfaces as said surfaces may be formed on the ends of the drums or parts of the drums without departing from the spirit and scope of my invention.

Having thus described my invention, what 125 I claim is:—

1. In a rope drum, in combination, a shaft, a driving member fixed thereto, two drums

one revoluble thereon and the other splined directly thereto to thereby revolve with the shaft in both directions, friction surfaces between said drums and also between one of said drums and said driving member and means whereby the pressure between said friction surfaces may be adjusted.

2. In a rope drum, in combination, the shaft, the spur wheel fixed thereon, the drum 10 revoluble thereon next said spur wheel, friction surfaces interposed between said spur wheel and revoluble drum, a drum splined directly to said shaft next said revoluble drum and revoluble in both directions with 15 the shaft, friction surfaces between said drums and means whereby the pressure between said friction surfaces may be adjusted.

3. In a rope drum, in combination, a shaft, a two-part drum, one part being splined directly to said shaft to rotate in both directions therewith and the other revoluble on 20 said shaft, a driving member fixed to said shaft, friction surfaces between said driving member and one of said drums, friction surfaces between said drums and mechanism 25

whereby the pressure between said friction surfaces is adjusted.

4. In a rope drum, in combination, a drum shaft, a driving member fixed to the shaft, a two-part drum on the shaft, one part being 30 fixed to the shaft to rotate therewith in both directions, and the other part being arranged between the splined part and the driving member, and freely revoluble relative to the shaft, both of said parts being 35 movable longitudinally of the shaft, clutch means for connecting the freely revoluble drum part and the driving member, and thrust means acting on the splined drum part to move both said parts longitudinally 40 of the shaft to connect said clutch means to couple the freely revoluble drum part and the driving member.

In testimony whereof I have signed my name to this specification in the presence of 45 two subscribing witnesses.

THOMAS SPENCER MILLER.
